BICYCLE FRAME

Viktor Schreckengost, Cleveland Heights, Ohio,
assignor to The Murray-Ohio Manufacturing
Company, Cleveland, Ohio, a corporation of
Ohio

Application April 27, 1953, Serial No. 24,678

Term of patent 14 years

(Cl. D90—8)

To all whom it may concern:

Be it known that I, Viktor Schreckengost, a citizen of the United States, residing at Cleveland Heights, county of Cuyahoga, and State of Ohio, having invented a new, original, and ornamental Design for a Bicycle Frame, of which the following is a specification, reference being had to the accompanying drawings, forming a part thereof.

In said annexed drawings:

Fig. 1 is a side elevational view of a bicycle frame showing my new design;

Fig. 2 is a top plan view of the bicycle frame shown in Fig. 1;

Fig. 3 is a front elevational view of the bicycle frame shown in Fig. 1;

Fig. 4 is a section showing the contour only as viewed at the line 4—4 in Fig. 1;

Fig. 5 is a section showing the contour only as viewed at the line 5—5 in Fig. 1; and

Fig. 6 is a section showing the contour only as viewed at the line 6—6 in Fig. 1.

The dominant features of my design reside in the portions shown in full lines.

I claim:

The ornamental design for a bicycle frame, substantially as shown and described.

VIKTOR SCHRECKENGOST.
